O. E. HUNT.
HYDROCARBON MOTOR.
APPLICATION FILED APR. 27, 1918.

1,402,863.

Patented Jan. 10, 1922.

UNITED STATES PATENT OFFICE.

ORMOND E. HUNT, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

1,402,863.

Specification of Letters Patent. Patented Jan. 10, 1922.

Application filed April 27, 1918. Serial No. 231,237.

To all whom it may concern:

Be it known that I, ORMOND E. HUNT, a citizen of the United States, and resident of Detroit, Wayne county, State of Michigan, have invented certain new and useful Improvements in Hydrocarbon Motors, of which the following is a specification.

This invention relates to hydrocarbon motors and particularly to the reduction 10 gearing between the crank shaft thereof and a propeller shaft, and the mounting of the parts.

One of the objects of the invention is to provide a construction that will permit of 15 unit assembly to thereby facilitate manufacture.

Another object of the invention is to provide a supporting bearing for the crank shaft beyond the driving gear thereof.

20 Another object of the invention is to provide a novel arrangement of supporting bearings for the driven propeller shaft.

Another object of the invention is to 25 mount the propeller shaft so that a gun may project into and shoot through it.

Other objects of the invention will appear 30 from the following description taken in connection with the drawings which form a part of the specification, and in which the figure is largely a longitudinal vertical section through a hydrocarbon motor embodying the invention, some of the parts being shown in elevation.

Referring to the drawing, 10 represents 35 a crank case or support or base of a hydrocarbon motor upon which cylinders 11 are mounted and in which is a crank shaft 12. The motor shown is of the type having two sets of cylinders side by side and the upper

40 part of the crank case between the sets of cylinders is formed with a support 13 for a quick firing gun, the barrel of the gun being supported in the part 14 and the recoil mechanism in the part 15. Such motors are intended for use in airplanes and it is intended 45 that the gun may project into the propeller shaft, hereinafter described, and shoot through it.

The front end 16 of the crank case supports 50 a plain bearing 17 for the crank shaft 12, this bearing being lubricated by means of a conduit 18 leading from any suitable pump, not shown.

The crank shaft 12 extends forwardly beyond the bearing 17 as shown at 19 and a

driving spur gear 20 is keyed thereon. A cover 21 is detachably secured to the forward end of the crank case as by bolts 22 and this cover together with the forward part of the crank case forms a compartment 60 23 which houses the gear 20 and the extended end 19 of the crank shaft 12.

Rotatably supported in the cover 21 is a propeller shaft 24 which is of tubular form to permit a gun at the rear end to fire 65 through it. Near its forward end the tubular shaft 24 is formed with an integral flange 25 to which a propeller 26 is rigidly secured as by bolts 27 and a removable flange 28. This constitutes a more rigid and 70 durable propeller attachment than can possibly be secured by the ordinary keyed construction between the propeller and the shaft. At the same time this flange construction precludes the possibility of assembling 75 any of the propeller shaft bearings from the forward end of the shaft.

Just rearwardly of the flange 25 the shaft 24 is formed with a shoulder 29 against which is an oil throw-off ring 30. Next to 80 the ring 30 is an annular roller bearing 31, the term "roller bearing" including rollers of all types such as balls, cylinders and cones. Next to the inner race of the bearing 31 is a spacing sleeve 32 which abuts against 85 the intermediate race 33 of a double thrust bearing 34. Next to the race 33 is a large spur gear 35 which is keyed to the shaft and which meshes with the gear 20 as shown in the drawing. Abutting against the hub of 90 the gear 35 is the inner race of another annular roller bearing 36 and a nut 37 is threaded on the shaft 24 and secures all of the parts thereon.

A plate 38 extends from the outside of the 95 cover 21 to the periphery of the shaft 24 adjacent the shoulder 29 and a packing 39 prevents the escape of lubricant around the shaft at that point. Two bearing receiving collars 40 and 41 enclose the bearings 31 and 100 34 and are secured to the cover 21 by a series of bolts 42, which bolts and their nuts 43 also secure the plate 38 in place. A bearing receiving collar 44 secured to a flange 45 of the front end of the crank case, receives 105 the outer race of the bearing 36 above referred to and said bearing is adapted to slide into and out of said collar 44 as the propeller shaft is put in place or removed therefrom.

The propeller shaft 24 extends somewhat rearwardly of the bearing 36 and into the tubular part 14 of the crank case which supports the gun. This rearward extension 46 of the propeller shaft is provided with a steadyng bearing 47 which may be a plain bearing as shown in the drawing and this bearing is particularly designed to prevent any of the products of combustion from the gun getting into the compartment 23 where the main bearings of the propeller shaft are mounted.

The cover 21 also supports a bearing 48, which is shown as a roller bearing, in line 15 with the plain bearing 17 of the crank shaft. This bearing 48 supports the forwardly extended end 19 of the crank shaft and the inner race is secured thereon by a nut 49. A bearing retaining collar 50 is seated in the 20 cover 21 and the bearing 48 is adapted to slide into this collar as the cover 21 is positioned on the front end of the crank case.

Other forms and modifications of the mechanism shown and described herein may 25 be made without departing from the spirit or scope of the invention.

Having thus described my invention, what I claim and desire to secure by Letters Patent is:

30 1. The combination with a hydrocarbon motor having a crank case and a crank shaft therein extending through the crank case, of a casing detachably secured to the crank case and forming a covering for said extended end of the crank shaft, and a roller bearing mounted in said casing and adapted to receive the end of said crank shaft.

2. The combination with a hydrocarbon motor having a crank case and a crank shaft 40 therein extending through the crank case, of a casing on the crank case forming a compartment around the extended end of said crank shaft, said compartment being separated from the interior of the crank case, 45 and a roller bearing in said casing for the end of said crank shaft.

3. The combination with a hydrocarbon motor having a crank case and a crank shaft mounted in plain bearings therein, the end

of said crank shaft extending through one 50 end of the crank case beyond the end bearing, a gear on the extended part of said shaft, a bearing for said shaft beyond said gear, and a casing supporting said latter bearing and enclosing said gear. 55

4. The combination with a support, of a propeller shaft, a pair of separated roller bearings for said shaft in said support, and a plain bearing for one end of said shaft.

5. The combination with a support, of a 60 hollow propeller shaft open at both ends and having an integral propeller flange, of a roller bearing for said shaft in said support adjacent said flange, and a plain bearing for the end of said shaft. 65

6. The combination with a support, of a hollow propeller shaft open at both ends and having an integral propeller flange, of radial and thrust bearings for said shaft in said support adjacent said flange, and a plain 70 bearing for the end of said shaft.

7. The combination with a support having a bearing receiving part, of a cover 75 adapted to be detachably connected to said support, a propeller shaft extending through said cover, bearings supporting said shaft in said cover, and a bearing surrounding a part of said shaft and adapted to enter said bearing receiving part as the cover is positioned against said support. 80

8. The combination with a support having a bearing receiving part, of a cover adapted to be detachably connected to said support, a propeller shaft extending through said cover, and bearings for said shaft in 85 said support and cover, substantially as described.

9. The combination with a hydrocarbon motor having a crank case forming a support, of a hollow propeller shaft geared to the motor and having an integral propeller flange, and a roller bearing and a plain bearing for said shaft in said support, said bearings being separated and one being at the 90 end of the shaft and the other being adjacent to the propeller flange. 95

In testimony whereof I affix my signature.
ORMOND E. HUNT.
